UNITED STATES PATENT OFFICE.

ZACHARIAS OLSSON, OF WESTPORT, CONNECTICUT, ASSIGNOR TO JAMES K. WHETEN,
OF NEW YORK, N. Y.

LAMP CONSTRUCTION.

Application filed October 12, 1923. Serial No. 668,090.

To all whom it may concern:

Be it known that I, ZACHARIAS OLSSON, a subject of the King of Sweden, and a resident of Westport, county of Fairfield, 5 and State of Connecticut, have invented an Improvement in Lamp Construction, of which the following is a specification.

This invention relates to lamp construction and with regard to its more specific 10 features to construction for lamps of the lantern type.

One of the objects of the invention is to provide a construction of the above nature capable of efficient and dependable operation. Another object is to provide a construction of the above nature strong and durable and adapted to withstand rough usage. Another object is to provide a device 15 of the above nature adapted to be employed in the open and to operate efficiently in all conditions of weather. Another object is to provide such a construction in which the parts are dependably assembled and yet readily accessible. Other objects will be in part 20 obvious or in part pointed out hereinafter.

The invention accordingly consists in the features of construction, combinations of elements, and arrangement of parts as will be exemplified in the structure to be hereinafter described and the scope of the application of which will be indicated in the following claims.

In the accompanying drawing there is shown a side elevation partly in section of 35 a lamp illustrating one of the various possible embodiments of this invention.

Referring now to the drawing in detail there is shown a base member 10 upon which the lamp is adapted to stand and which is 40 hollow providing a reservoir for oil or other fuel adapted to supply the light. Supported upon the upper surface of the base member 10 is a burner 11 which may comprise a wick passing downwardly therethrough into the oil reservoir in the usual manner and a regulating device 12 for adjustment of the wick. The flame from the burner 11 is represented at 13.

Secured to the base member 10, as for 45 example by rivets 14, is a plurality of frame members 15 shown as four in number extending upwardly and arching outwardly as shown. The frame members 15 are preferably formed of suitable wire and at their upper ends are joined to a lateral ring shaped

frame member 16 of similar material. A second ring shaped frame member 17 similar to the member 16 rests against the upper surface thereof and has connected thereto upwardly extending curved frame members 60 18 similar to the lower frame members 15. The upper frame members 17 and 18 are joined to the lower frame members 15 and 16 by means of a suitable hinged connection as 19 at one side of the lamp and at the other 65 side thereof are provided with a suitable detachable catch 20.

To the upper ends of the frame members 18 is secured as by means of rivets 21 a casing member 22 preferably of substantially cylindrical shape and preferably formed of sheet metal. The upper end of the casing member 22 is closed by a roof or cap member 23 formed of sheet metal and secured to the upper end of the casing 22 in any desired manner as by welding. The casing 22 adjacent its upper end is provided with a plurality of lateral openings 24 for the admission of air thereinto as will be later described and the edge portion 23a of the roof 80 23 overhangs these openings to shield the same from the effects of wind.

Inside the casing 22, extending upwardly through the cap 23 and secured to the latter as by welding along the line 25 is a sheet 85 metal member 26 of cylindrical form positioned above the burner 11 and thus providing a discharge passage or chimney for the heated gases or products of combustion from the burner. At the outer end of the chimney 26 is a sheet metal cap member 27 supported and spaced from the end of the chimney as by brackets 28, for example. The edge portion 27a of the cap 27 overhangs the end of the chimney and the products of combustion 90 are directed by the cap 27 over the edge of the chimney and downwardly so that the exhaust passage is shielded from wind and back-draft down the chimney 26 is effectively avoided.

Depending from the open lower end of the casing 22 and substantially registering therewith is a globe 29 of glass or other suitable translucent or transparent material. The globe 29 is secured to the casing 22, for example, by means of a clamping ring 30 engaging a flange 31 upon the lower end of the casing 22 and the upper flanged rim 32 of the globe 29. The casing 22 and the globe 29 are of such length relative to the length 100 105 110

of the frame members 15 and 18 that the open lower end of the globe 29 substantially rests upon the upper surface of the base member 10 fitting within a flange 33 thereon to form a substantially tight joint.

Depending from the lower end of the chimney 26 and substantially registering therewith is an inner globe member 34 extending about the burner 11. The globe 34 is secured to the chimney 26, for example, by means of a clamping ring 35 engaging a flanged portion 36 of the chimney and the upper rim 37 of the globe. The open lower end of the globe 34 is spaced from the upper surface of the base member 10 thus providing a passage therebetween.

Considering now the operation of this apparatus; air for combustion at the burner 11 is admitted at the openings 24, passes downwardly through the passage provided between the casing 22 and the chimney 26 and between the globes 29 and 34 and thence upwardly to the interior of the globe 34 through its open lower end to supply the burner therein. The products of combustion and heated gases from the burner 11 pass upwardly through the inner globe 34 and the chimney 26 and are discharged beneath the overhanging edge of the cap 27. As the air for combustion enters the openings 24 it impinges against the surface of the chimney 26 which is heated by the products of combustion passing upwardly therethrough. The air then passes downwardly along the chimney 26 and the globe 34 which are continually heated by products of combustion passing upwardly therethrough and thus when the air for combustion reaches the burner 11 it is pre-heated to an extent which renders it exceedingly advantageous at the burner. This pre-heating of the air accordingly facilitates combustion at the burner and makes for a steady, even burning light. Furthermore, as has been described, the inlet openings for air and the outlet from the chimney are effectively shielded from wind so that a regular uniform draft is supplied to the burner and back-draft is avoided.

The lamp may be provided with a suitable handle 38 secured, for example, to the cap member 23 as at 39. In the construction shown in the drawing the two globes 29 and 34 and the parts from which they are suspended are supported by the frame members 17 and 18. Therefore by releasing the catch 20 and swinging the upper portion of the lantern upwardly about the hinge 19 the globes are drawn away from the burner thus permitting immediate and convenient access to the burner and its adjusting mechanism. The frame members 15, 16, 17 and 18 serve to form a protection for the globes about the light. The entire construction is one which is strong and sturdy throughout,

capable of dependably standing up under rough usage.

As many possible embodiments may be made of the above invention and as many changes might be made in the embodiment above set forth, it is to be understood that all matter hereinbefore set forth is to be interpreted as illustrative and not in a limiting sense.

I claim as my invention:

1. In lamp construction, in combination, a base, a burner mounted thereon, a chimney above said burner for discharging products of combustion, a globe secured to said chimney at its upper end and depending from said chimney above said burner, a casing about said chimney secured thereto and spaced therefrom and forming a passage for air thereabout, said casing having adjacent its top portion openings for the admission of air to said passage, a cover for said casing through which said chimney projects, said cover overhanging the top of said casing to protect said air openings from the effects of winds, a globe secured to said casing at its upper end and depending from said casing exterior of said first globe meeting said base member at its lower end and forming a continuation of said air passage to the lower end of said inner globe, and frame members forming a hinged connection between said casing and said base, permitting swinging of said two globes as a unit upwardly from about said burner.

2. In lamp construction, in combination, a base, a burner mounted thereon, a chimney above said burner for discharging products of combustion, a globe secured to said chimney at its upper end and depending freely from said chimney about said burner and open at its lower end, a casing about said chimney secured thereto and spaced therefrom and forming a passage for air thereabout, said casing being adapted to admit air at its upper portion, a globe secured to said casing at its upper end and depending from said casing exterior of said first globe meeting said base member at its lower end and forming a continuation of said air passage to the open lower end of said inner globe, a wire frame work extending upwardly from said base member exterior of said outer globe, a wire frame work extending downwardly from said casing resting upon said first frame work substantially midway between said casing and said base and supporting said casing, and a hinged connection between said two frame works whereby said two globes may be swung as a unit upwardly about said burner.

3. In lamp construction, in combination, a base a burner mounted thereon, a chimney above said burner for discharging products of combustion, a cap over said chimney and overhanging the upper edge thereof to pro-

TECT said burner from back draft, a globe secured at its upper end to said chimney and depending from said chimney about said burner, and open at its lower end, a casing 5 about said chimney secured thereto and spaced therefrom and forming a passage for air thereabout, said casing having adjacent its top portion openings for the admission of air to said passage, a cover for said casing 10 through which said chimney projects, said cover overhanging the top of said casing to protect said air openings from the effects of wind, a globe secured at its upper end to said casing and depending from said casing 15 exterior of said first globe meeting said base member at its lower end and forming a con- tinuation of said air passage to the lower end of said inner globe, a frame work extending upwardly from said base member exterior of said outer globe, a frame work extending 20 downwardly from said casing and resting upon said first frame work substantially midway between said casing and said base, and a hinged connection between said two frame works whereby said two globes may 25 be swung as a unit upwardly from about said burner.

In testimony whereof, I have signed my name to this specification this 8th day of October, 1923.

ZACHARIAS OLSSON.
